UNITED STATES PATENT OFFICE.

WILLIAM LYNCH, OF BROOKLYN, NEW YORK.

CRATE FOR MILK BOTTLES.

1,426,304.

Specification of Letters Patent. Patented Aug. 15, 1922.

Application filed November 3, 1921. Serial No. 512,508.

To all whom it may concern:

Be it known that I, WILLIAM LYNCH, a citizen of the United States, and a resident of the city of New York, borough of Brooklyn, in the county of Kings and State of New York, have invented a new and Improved Crate for Milk Bottles, of which the following is a full, clear, and exact description.

10 The present invention relates to new and useful improvements in crates, boxes and the like, and it pertains more particularly to a crate or box containing milk bottles.

In the present handling of milk bottles, 15 it is generally required that the bottles be sterilized after each use thereof, and it is also the general practice to sterilize these bottles directly in the crates in which they are shipped and handled in order that the 20 crates also may be subjected to the sterilizing action. The crates with the bottles in inverted position are passed through suitable sterilizing apparatus consisting of various jets of water of different degrees of 25 temperature. It frequently happens that the bottles when inverted in the crate do not properly position themselves, and when this is the case, as the crates pass through the sterilizing apparatus the bottles will not be 30 in proper position to receive the various jets of water, and the washing operation, therefore, is inefficiently carried out.

It has been the common practice to provide metal supporting elements in the crates 35 upon which the bottles rest, and in the ordinary form of such devices, when the bottles are inverted, the mouths of the bottles become chipped owing to their contact with these metal supports, and thus the bottles 40 are rendered useless for subsequent operations.

It is one of the primary objects of the present invention to construct a crate which is especially adapted for properly positioning the bottles during the sterilizing operation.

It is a further object of the invention to provide a new and improved form of metallic supporting means adapted to center 50 the bottles when in inverted position in the crate.

It is a still further object of the invention to so construct this metal supporting element that it will engage only the en-

larged portion common to the mouths of 55 milk bottles of the conventional type, and owing to its engagement with this portion of the bottle, the chance or liability of the bottle becoming chipped by reason of its contact with the metal supporting member 60 is minimized.

With the above and other objects in view, reference is had to the accompanying drawings, in which

Figure 1 is a sectional view of a crate or 65 box constructed in accordance with the present invention;

Fig. 2 is a detail view partly in section, showing the manner of engagement of the mouth of the bottle with the metallic supporting member when the bottle is properly positioned within the crate;

Fig. 3 is a similar view showing the bottle angularly disposed and the manner in which it is automatically centered when 75 placed in inverted position in the crate.

Referring more particularly to the drawings, the reference character 5 designates the crate, and said crate is constructed in the ordinary manner with a plurality of 80 transverse partitions 6 adapted to form spaces within which the bottles 7 are received.

Extending preferably longitudinally of the crate or box 5 and arranged in spaced 85 relation in the bottom thereof, is a plurality of metallic supporting members 8. These metallic supporting members 8 are in the form of steel wires, and have their ends angularly bent as indicated by the reference 90 character 9, and passed into openings in the frame members of the box in order to secure the metallic supporting members 8 in place. These members 8 are clearly shown in Figs. 95 2 and 3, and said members are bent to form 95 depressed portions indicated by the reference character 10. The angles of the sides of each of these depressed portions are different in that the inner angle 11 is sharper or more abrupt than is the outer angle 12. 100

By this construction it is apparent that as the bottle is placed in inverted position within the crate, if the bottle be inserted in a true vertical plane, the thickened portion 14 of the mouth thereof will engage the 105 less abrupt angle 12 of the depressed portion 10, as is clearly shown in Fig. 2, and the bottle will be supported in this manner

with the inner marginal edge of its mouth out of contact with that portion 20 of the metallic supporting member which lies between the depressed portions 10.

5 Assuming, however, that the bottle is not inserted within the crate in a true vertical plane but is inserted at an angle as shown in Fig. 3, with the thicker portion of the neck of the bottle engaging either of the less 10 abrupt portions 12 of the depressed portion 10 of the metallic members 8, the bottle will then automatically assume the position shown in Fig. 2, which is in the true vertical plane. Owing to the intermediate portion 15 20 of the supporting members 8 projecting upwardly into the mouth of the bottles, it is apparent that the bottles cannot shift relatively to the supporting members, and, therefore, the bottles will at all times be 25 properly centered in order to receive the jets of the sterilizing apparatus.

From the foregoing it is apparent that as the bottles are inserted in the crate, the shoulder 25 of the mouth of the bottle can 25 at no time engage any portion of the metallic supporting member, and inasmuch as only the thickened portion 14 of the mouth 30 of the bottle engages this metallic member, which thickened portion will withstand 35 shocks and jars, the tendency of the bottles to chip and break is greatly reduced. Therefore, in employing a crate of this character the life of the bottles is greatly increased over bottles employed with the ordinary supporting member in which the shoulder portion 25 of the bottle is continuously subject-

ed to shocks and is consequently chipped and fractured.

I claim:

1. In a crate, a supporting member, said supporting member being crimped to provide depressed portions arranged in spaced pairs, the legs of each of said depressed portions being of different angles.
2. In a crate, a bottle-supporting member comprising a wire extending longitudinally of the crate and provided with depressed portions adapted to receive the mouth of a bottle supported therein in such a manner that the interior of the mouth of said bottle will at all times be out of contact with the bottle-supporting member.
3. In a milk-bottle crate, a supporting member comprising a strand of wire anchored in the frame of the crate and depressed portions formed in said wire, said depressed portions being arranged in pairs and having their opposite sides angularly disposed with respect to each other in such a manner that the milk-bottle will be supported within the depressed portion on the outer angles thereof, substantially as described.
4. In a milk-bottle crate, a bottle-supporting element comprising a strand of wire having substantially V-shaped portions formed therein and arranged in pairs, the legs of said V-shaped portions being arranged at different degrees of angle, as and for the purpose set forth.

WILLIAM LYNCH.
